UNITED STATES PATENT OFFICE.

FRANK W. MILLER, OF CHICAGO, ILLINOIS, ASSIGNOR OF ONE-HALF TO CLARENCE D. BAUERS, OF CHICAGO, ILLINOIS.

BOILER WASHING AND FILLING SYSTEM.

1,032,076.

Specification of Letters Patent. Patented July 9, 1912.

Application filed November 28, 1910. Serial No. 594,437.

To all whom it may concern:

Be it known that I, FRANK W. MILLER, a citizen of the United States, residing at Chicago, in the county of Cook and State 5 of Illinois, have invented certain new and useful Improvements in Boiler Washing and Filling Systems, of which the following is a specification.

This invention relates in general to boiler 10 washing and filling systems and more particularly to a system for employing the heat units of the steam and water blown off from a locomotive in a roundhouse for heating clean fresh water to be used for washing 15 out and refilling locomotive boilers.

One of the objects of the present invention is to partially heat clean fresh water in a reservoir for washing out and refilling purposes by discharging the blown-off steam 20 and water through a coil located in the reservoir.

Another object is to utilize the exhaust steam from the stationary boilers usually located in the roundhouse and adjacent 25 shops for further heating the fresh water in the reservoir.

Still another object is to regulate the temperature of the water in the reservoir by automatically controlling the admission 30 of live steam thereto.

A further object is the provision of means whereby the heated water in the reservoir may be conducted directly to the locomotive 35 boiler for washing out purposes or may be conveyed through a heater where it is further heated so that it may be used for refilling the locomotive boiler.

An additional object is the provision of a union provided with an offset shoulder 40 in the blow-off pipe and a scale pocket connected to the union so that the scale and sediment blown off from the boiler will be collected in the scale pocket.

Still another object is to maintain a circulation of water in the washout and re- 45 filling lines by connecting the ends of these lines with the blow-off line thereby maintaining at all times a supply of heated water in the washout and refilling lines 50 without the necessity of using additional return or circulating pipes.

Other objects and advantages of this invention will be apparent as it is better understood by reference to the following description when taken in connection with the 55 accompanying drawings illustrating a preferred embodiment thereof.

Referring to the drawings—Figure 1 is a side elevation partially in section of a boiler washing and filling system embodying my 60 invention. Fig. 2 is an end elevation thereof. Fig. 3 is an elevation of the ends of the washout, refilling and blow-off lines and the drops connected therewith; and Fig. 4 is a sectional view on the line 4—4 of Fig. 1. 65

In the installation of this boiler washing and refilling system the heaters and reservoirs for heating the water to be used for washout and refilling purposes are disposed in any convenient location either within or 70 outside the roundhouse proper, and the roundhouse is equipped with lines of pipe running preferably along the ceiling over the locomotive stalls or pits, said pipe lines being connected at one end with the reservoir or heater in a manner later to be described and being adapted to convey water 75 from the reservoir or heater to the remotest pit of the roundhouse and to conduct the blown-off steam and water from the locomotives disposed over the various pits back to the heater and reservoir. These pipe lines comprise essentially a blow-off main 5, a hot water washout main 6 and a refilling water main 7. The mains, as will be understood, are disposed adjacent the various pits of the roundhouse and are of sufficient size to take care of a number of locomotive 80 boilers simultaneously. A post or upright 8 is usually located between each pair of pits 85 and the drops connecting the various pipe lines are usually positioned adjacent to and if desired fastened to and partially supported by this upright. Each set of drops is adapted to be connected with a boiler which 90 may be positioned over the pit on either side thereof.

The blow-off main 5 has connected thereto a blow-off drop 9 which may be provided at its lower end with a flexible pipe or hose 100 10 adapted to be connected with a locomotive, boiler diagrammatically illustrated at

11. The blow-off drop is preferably provided with a check-valve 12 which prevents a reverse flow of the steam and water in the blow-off pipe back to the boiler. A drop 13 is connected to the washout main 6 and a similar drop 14 is connected with the refilling main 7. It will be understood, of course, that flexible pipes or hose 10 are secured to the lower end of each of the drops 10 13 and 14 and are adapted to be connected with a boiler on either side of the drops. The drops 13, 14 and 9 are provided with controlling valves 15, 16 and 17 respectively, by means of which communication between 15 any of the lines and the boiler may be controlled.

In Fig. 3 it will be observed that the last set of drops at the ends of the lines is shown. Since it is desirable to maintain 20 water of a predetermined temperature in the washout and refilling lines at all times, it has been found expedient to maintain a circulation of the water in these lines in order that the temperature at the remotest drops 25 may not fall below that required for washing out and refilling purposes. In order to effect this circulation in the washout and refilling mains without installing additional return pipes through which the water may 30 be returned to the heater or reservoir, I have connected the outer ends of the refilling and washout lines 6 and 7 respectively, with the end of the blow-off line 5. This method of connecting permits the water in the blow-off and refilling lines to pass into the blow-off line and be returned to the heater and reservoir thus establishing the desired circulation and maintaining the water at all 35 points along the washout and refilling lines 40 at the required temperature. In the form of connection shown in Fig. 3, I have attached to the end of the washout line 6, a T 18 which is connected by short pieces of pipe and elbows 19 and 20 with the refilling main 45 and blow-off main, respectively. It is usually desirable to place either check-valves or hand-valves 21 and 22 in the washout and refilling mains, respectively, to prevent the 50 blown-off water from backing up into the mains and also to limit the amount of water which will be circulated back to the heater through the blow-off main since it is only necessary to maintain a slight circulation in the washout and refilling mains to preserve 55 the proper temperature of the water therein.

The blow-off main 5 communicates with one end of a filling water heater 23 which is provided with inner heads 24 and 25 and with a baffle-plate 26 above which the blow-off main communicates with the heater. A plurality of tubes or flues 27 are fixedly secured at either end to the inner heads to establish communication between the chamber outside the head 25 and the chambers

above and below the baffle-plate 26. These 65 tubes are separated one from the other to afford considerable open space around them for the storage of the water which is to be heated by the tubes and subsequently used for refilling purposes. 70

A wash water reservoir 28 is positioned beneath the filling water heater upon suitable saddles or other supports 29, while the heater 23 is preferably carried upon girders or I-beams 30 directly above the reservoir. 75 It will be obvious, however, that any other preferred arrangement of the reservoirs and heater may be resorted to if found more convenient. Water is supplied to the reservoir from a pipe 31 which is connected with any 80 suitable source of water supply, the water being admitted to the top of the reservoir through a short pipe 32 and the height of water in the reservoir being maintained by a float 33 controlling a water-valve 34 positioned in the pipe 31, as shown in Fig. 1. An overflow pipe 35 is provided as a safeguard to prevent the reservoir from filling to the top in case water-valve 34 fails to shut off the water, and in order that the 90 water may not be siphoned from the reservoir by this overflow, an air-vent 36 is situated at the crown of the overflow. It will be understood, of course, that the overflow pipe 35 discharges into the sewer or any 95 other preferred means of disposing of the overflow.

Within the reservoir there is arranged a loop or coil of pipe 37 which preferably extends from end to end of the reservoir and 100 is connected at its intake end to the chamber in the heater 23 beneath the baffle-plate 26 by pipes 38 and 39. The discharge end of the coil is connected with the pipe 39 which discharges at its lower end into a 105 sewer, through a short connecting pipe provided with a T-fitting 40 and hand-valves 41 and 42. With both of the valves 41 and 42 open it will be evident that the blown-off steam and water will be discharged from the 110 upper heater through pipes 38 and 39, and if valve 43 located in pipe 39 is open the blown-off products will be discharged directly to the sewer. In the normal operation of the device, however, valve 43 is maintained closed thereby compelling the blown-off steam and water discharged from the heater to circulate through the coil 37 and discharge through the fitting 40 into the pipe 39 below the valve 43 and subsequently 115 to the sewer. Valve 41 is usually closed and valve 42 is open, the water then rising in pipe 44 to the cross-connecting pipe 45 before it can enter the discharge pipe 39. It will be apparent that the pipe 41 is positioned slightly above the central portion of the coil 37 so that water is maintained at 120 all times in the coil to the height of pipe 125

45. In order to prevent the water and steam in the coil from flowing in a reverse direction a check-valve 46 is preferably provided. For the purpose of draining the heater in 5 case the coil or the upper portion of the pipe 39 should become stopped up, the upper end of the pipe 44 is connected with the heater, as shown in Fig. 1. The valve 47 with which this pipe is supplied near its 10 upper end, is normally maintained in closed position, but in case of emergency when it is desired to drain the upper heater through this pipe, valve 47 may be opened and valve 42 closed, whereupon the blown-off contents 15 of the upper heater may be discharged to the sewer either through the cross-connection 45 or through the valve 41 and the pipe 39.

In order that blown-off steam and water 20 may be admitted to the reservoir, and mingled with the washout and refilling water therein if desired, the coil 37 is provided with valves 48 and 49 which are equipped with operating handles 50 and 51, respectively, by means of which the valves may be manipulated from outside the reservoir. By adjusting these valves any desired quantity of the blown-off steam and water may be discharged from the coil directly into the 30 reservoir to be mixed with the water therein, and utilized for washout and refilling purposes. The contents of the reservoir may be drained into the sewer whenever desired by opening valve 52 which establishes communication through pipes 53 and 54 between the reservoir and the sewer.

A fitting 55 is located in the blow-off main 5, said fitting being in the form of a T with a lateral shoulder which forms a right 40 angled connection between the main portion 5 of the blow-off main and the short branch 5'. The bottom branch of the fitting is connected with a pipe 56 which discharges into a scale pocket 57, while the 45 upper branch communicates with a pipe 58 leading to the power boilers of the shops which are usually located nearby, through a connecting pipe 59. The exhaust steam from the power boilers is thus saved and 50 conducted by the pipes 58 and 59 to the fitting 55 from whence it is conducted by the blow-off branch 5' to the filling water heater.

A check-valve 60 is provided in the blow-off main 5 to prevent the exhaust steam which enters through the pipe 59 from being conducted through the blow-off main to the drops when the pressure in the exhaust pipe 58 exceeds that in the blow-off 55 main. Likewise a check-valve 61 is provided in the connecting pipe 59 to prevent blown-off steam from discharging back into the exhaust pipe when pressure in the blow-off main exceeds that in the exhaust line 58.

The lower end of the scale pocket 57 is connected with the sewer through a short connection 62 which is controlled by a hand-valve 63.

When the blown-off steam and water are discharged through the blow-off main 5 70 they enter the fitting 55 and strike against the wall which is disposed opposite the discharge opening of the main pipe 5. The steam and water will be deflected by this wall, and any scale, sediment or other solid 75 matter carried by the blown-off water will be deposited in the scale pocket 57 while the steam and water will pass on through the branch 5' into the heater. If at any time it should become desirable to blow off the 80 steam and water from the boiler directly to the sewer this may be accomplished by closing the hand-valve 64 disposed in the branch 5' and opening the valve 63 located in the connection between the bottom of the 85 scale pocket and the sewer. The valve 63 is also opened whenever it is desired to clean the scale pocket.

The exhaust steam pipe 58 is extended beyond its connection with the pipe 59 and 90 communicates with the top of the reservoir through the short pipe 32. This connection of the exhaust steam pipe to the reservoir is established for the purpose of conducting the exhaust steam to the reservoir for heating 95 the water therein when the pressure in the blow-off line is great enough to maintain the check-valve 61 closed, thereby preventing the passage of the exhaust steam into the heater with the blown-off products. In 100 order to prevent a reverse flow of the steam in the exhaust pipe a check-valve 65 may be located in the pipe 58. It will be evident that the fresh cold water in the pipe 31 and the exhaust steam in the pipe 58 are 105 admitted through the same short connecting pipe 32, thereby permitting the steam and water to be mixed and a large proportion of the steam to be condensed before entering the reservoir.

If the blown-off products in the coil 37 and the exhaust steam admitted through the pipe 58 are not sufficient to maintain the water in the reservoir 28 at high enough 115 temperature for washing out purposes, the temperature of said water may be raised by the admission of live steam to the reservoir. A pipe 66 is accordingly provided which enters the reservoir near the top and discharges below the surface of the water. 120 A thermostat 67 of any preferred type is mounted at the outlet end of the reservoir and is connected by a link 68 or other suitable connection with a controlling valve 69 which controls the admission of live 125 steam to the reservoir. The thermostat may be set so as to deliver steam to the reservoir when the temperature of the water falls

below that required for washing out purposes.

A pump 70 of any well known or preferred type has its intake 71 connected with the reservoir, as shown in Fig. 1, and a strainer box 72 is preferably disposed across the intake to prevent sediment and solid particles from being drawn into the pump. The water drawn from the reservoir is discharged from the pump into the pipe 73 which is connected with the washout line 6. A branch 74 provided with a valve 75 also connects the discharge pipe 73 with the chamber between the inner heads of the heater 23. When it is desired to use the water in the reservoir 28 for washing out purposes the valve 75 is closed and valve 76 located in the washout line 6 is open, thereby permitting the water to be pumped from the reservoir and delivered to the washout line from whence it is conducted through the drops 13 to a boiler for washing out purposes. When the boiler is to be refilled the valve 76 may be closed and the valve 75 opened, thereby causing the water to be pumped from the reservoir into the heater from whence it is delivered to the boiler for refilling purposes through the refilling line 7 connected with the top of the heater, as shown in Fig. 1. The pump intake pipe 71 is also connected with the pipe 54 leading to the sewer and by opening the valve 77 the reservoir and strainer box may be drained into the sewer, as will be readily understood. From the above description it will be evident that the blown-off products from a boiler are circulated through the tubes in the heater, then through the coil in the reservoir, and are subsequently discharged into the sewer, the sediment and solid particles carried by the blown-off being deposited in the scale pocket 57. In order that a vacuum may not be formed in the heater or in the coil disposed in the reservoir by condensation of the blown-off steam the pipe 39 is extended preferably up through the roof of the roundhouse and is provided with a back pressure valve 78. The heater may be equipped with a thermometer 79 and a safety valve 80 if desired. The water which is to be employed for both washout and refilling purposes is delivered to the reservoir from a suitable supply through the pipe 31, and this water after being heated by the coil 37, the exhaust steam delivered by the pipe 58 and the live steam admitted through the pipe 66, is pumped to the washout line 6 and also into the heater around the tubes 27 where it is further heated for refilling purposes by the blown-off steam and water. The refilling water in the heater may be drained into the reservoir when desired through a pipe 81 provided with a suitable valve 82.

It will be evident that this system transfers the heat units of the blown-off steam and water to clean fresh water which is used for washing out and subsequently refilling the boilers, and that the heat units of the exhaust steam from the power boilers which is ordinarily permitted to go to waste is conserved and employed for heating the refilling and washout water. 65 70

While the particular embodiment of my invention which has been chosen for the purpose of illustration in this application has been specifically described, it will be apparent that various changes in the size, proportion and details of construction of the various parts may be resorted to without departing from the spirit of the invention or sacrificing any of the advantages thereof. 75 80

What I desire to claim is:

1. A boiler washing and filling system comprising a filling water heater, means for conducting the blown-off steam and water from the boiler to said heater, a washout and refilling water reservoir, a coil arranged in said reservoir, connections from said coil to the filling water heater whereby the blown-off steam and water are conducted from said heater through the coil to a sewer, means for supplying water to said reservoir where it is partially heated by said coil, and means for conveying said partially heated water to said heater where it is further heated by said blown-off steam and water. 85 90 95

2. A boiler washing and filling system comprising a filling water heater, a washout and filling water reservoir, a coil arranged in said reservoir, connections whereby the steam and water blown off from a boiler are conducted through said heater into said coil, means for maintaining a predetermined water level in said coil, means for maintaining a predetermined level of water in said reservoir around the coil, and means for conveying said water from the reservoir to a boiler for washout and refilling purposes. 100 105 110

3. A boiler washing and filling system, comprising a filling water heater, a blow-off line for conducting blown-off steam and water from a boiler to said heater, a washout and refilling water reservoir, a coil arranged therein, means for conducting the blown-off steam and water together from said heater to said coil, means for permitting a portion of said steam and water to escape from said coil into said reservoir to mingle with the water contained therein, and a discharge pipe through which the remainder of the blown-off steam and water is discharged from the coil. 115 120 125

4. In a boiler washing and filling system, the combination of a filling water heater, a reservoir for washout and refilling water, means for conducting the blown-off steam

and water from a boiler to said heater, a coil arranged in said reservoir, connections whereby the blown-off steam and water are conducted from the heater to said coil, 5 means for supplying water to said reservoir around the coil, and means permitting a desired proportion of the blown-off contents contained in the coil to escape therefrom and mingle with the contents of said reservoir.

10 5. In a boiler washing and filling system, the combination of a filling water heater, a reservoir adapted to contain water to be used for washout and refilling purposes, 15 means for conducting the blown-off steam and water from a boiler to said heater, means for heating the contents of the reservoir by the blown-off water and steam discharged from said heater, means for conducting water from said reservoir to a boiler for washout purposes, and a connection for conducting water from said reservoir to the heater where it is further heated by the blown-off steam and water for refilling purposes.

20 6. In a boiler washing and filling system, the combination of a filling water heater, means for conveying blown-off steam and water from a boiler thereto, a reservoir 30 adapted to contain washout and refilling water, a coil arranged in said reservoir, connections from said heater to said coil whereby the blown-off steam and water are conducted from said heater to said coil, means 35 whereby blown-off steam and water in the coil may be permitted to escape into the reservoir, means for maintaining a predetermined level of water in said reservoir, and an overflow connection from said coil 40 to a sewer adapted to maintain a predetermined water level in said coil.

7. A boiler washing and filling system, comprising a filling water heater, a reservoir, and means for discharging the blown-off steam and water from a boiler together 45 through said heater and reservoir successively to heat the contents of said heater and reservoir.

8. A boiler washing and filling system, comprising a filling water heater, a reservoir, and means for conveying unseparated through said heater and reservoir the blown-off steam and water from a locomotive boiler.

55 9. A boiler washing and filling system, comprising a filling water heater, a reservoir, means for conveying unseparated through said heater and reservoir the blown-off steam and water from a locomotive boiler, and means for permitting a portion of said blown-off steam and water to mingle with the contents of the reservoir.

60 10. A boiler washing and filling system, comprising a filling water heater, a reser-

voir, means for maintaining a predetermined level of water in said reservoir, means for conveying unseparated through said heater and reservoir the blown-off steam and water from a locomotive boiler, and a pump for delivering water from said reservoir to the heater, and to a wash-out line simultaneously.

11. A boiler washing and filling system, comprising a filling water heater, a reservoir, means for conveying the blown-off products of a locomotive boiler through said heater and reservoir successively to heat the contents thereof, means for supplying water to said reservoir, and means for conveying the exhaust steam from a power plant to the water inlet to said reservoir whereby said steam is condensed and discharged into the reservoir.

12. In a boiler washing and filling system, the combination of a reservoir, means for supplying water thereto, a heater, a blow-off line for conducting blown-off products from a boiler to said heater, a washout line for conducting water from said reservoir to the boiler for washing out purposes, 90 and means for connecting said washout line with said blow-off line whereby to maintain a circulation of water in the washout line.

13. In a boiler washing and filling system, the combination of a reservoir, means for supplying water thereto, a heater, means for conducting water from said reservoir to the heater, a blow-off line for discharging the blown-off products from a 100 boiler to said heater, a refilling line for conducting the heated water from said heater to the boiler for refilling purposes, and a connection between said blow-off and refilling lines whereby a circulation of water is 105 maintained in the refilling line.

14. In a boiler washing and filling system, the combination of a reservoir, means for supplying water thereto, a filling water heater, means for conducting water from 110 said reservoir to the heater where it is heated for boiler filling purposes, a refilling line for conducting said heated water to the boiler, a blow-off line for conducting the blown-off products of a boiler to said heater, a washout line for conducting water from the reservoir to the boiler for washout purposes, a connection between said washout line and said blow-off line, and a connection between said refilling line and said 115 blow-off line whereby a circulation of water is maintained in said washout and refilling lines through the blow-off line.

15. In a boiler washing and filling system, the combination of a blow-off main, a washout main, a refilling main, and means independent of the roundhouse drops for connecting the washout and refilling mains

with the blow-off main whereby said blow-off main serves as a return pipe for both the washout and refilling mains.

16. In a boiler washing and filling system, the combination of a blow-off main, a wash-out main, and connections independent of the roundhouse drops between said mains whereby the blow-off main serves as a return or circulating pipe for the wash-out main.

17. In a boiler washing and filling sys-

tem, the combination of a blow-off main, a refilling main, and connections independent of the roundhouse drops between said mains whereby the blow-off main serves as 15 a return or circulating pipe for the refilling main.

FRANK W. MILLER.
